UNITED STATES PATENT OFFICE

162,803

PAIR OF SUNGLASSES

Natalie de L. Feins, Beverly Hills, Calif.

Application April 27, 1949, Serial No. 2,285

Term of patent 3½ years

(Cl. D57—1)

To all whom it may concern:

Be it known that I, Natalie de L. Feins, a citizen of the United States of America, residing in the city of Beverly Hills, county of Los Angeles, State of California, have invented a new, original, and ornamental Design for Pair of Sunglasses, of which the following is a specification, reference being had to the accompanying drawing, forming a part thereof.

Figure 1 is a front elevational view of a pair of sunglasses, showing my new design;

Figure 2 is a top plan view thereof, one of the temples being shown in a broken away condition for convenience of illustration;

Figure 3 is a side elevational view thereof, the opposite side presenting substantially the same appearance as the side shown; and

Figure 4 is a fragmentary front elevational view, on an enlarged scale, looking in the direction of the arrows 4—4 in Figure 2.

I claim:

The ornamental design for pair of sunglasses, substantially as shown and described.

NATALIE DE L. FEINS.
